UNITED STATES PATENT OFFICE.

LESLIE DANA, OF ST. LOUIS, MISSOURI.

AUTOMATIC REGULATOR.

Application filed June 4, 1926. Serial No. 113,696.

This invention relates to automatic damper regulators for stoves, furnaces and heating apparatus generally, more particularly for coal or other solid fuel heating apparatus for rooms, dwellings and small buildings, of the type shown in my prior patent granted to me on December 30, 1924, No. 1,521,436.

My invention aims to improve generally such devices by providing a simple, reliable and efficient automatic regulator capable of controlling both the check and draft dampers.

Furthermore, the automatic control of one or both of the check and draft dampers makes it desirable to lock the regulator so as to open the check damper and close the draft damper at times thereby to prevent the rapid consumption of fuel when a hot fire is not required, as for instance during the night, and a further aim is the provision of means cooperating with the automatic control means for this purpose.

Further aims and advantages of the invention appear hereinafter in connection with the description of the embodiment thereof shown in the accompanying drawings, wherein

Fig. 1 is a side elevation of my improved regulator applied to an ordinary domestic heater;

Fig. 2 is a rear elevation of the regulator and a portion of the heater, looking at it from the right of Fig. 1, and

Fig. 3 is a detail vertical sectional view of the regulator illustrating the check damper latched in open position in full lines and in closed position in dotted lines.

Figure 4 is a detailed perspective view of the night latch and associated mechanism.

In the illustrative embodiment of the invention shown in the drawings, a thermal regulator of the bimetallic type is shown applied to the check damper 10, which is hinged to open downwardly by gravity on the lower edge of an opening into the outlet flue 11 of an ordinary room type heater 12 having a bottom draft damper 13 of usual form, located preferably on the rear side of the heater so as to be in vertical alignment with the check damper 10, as shown in Fig. 1.

The automatic regulator for the check damper may be of any suitable construction, but preferably is of the type shown and described in my prior Patent, No. 1,521,436,

and comprises a housing 14 having perforated walls 15 enclosing a thermostatic element 16 and a check damper operating member 17 connected directly to the check damper 10 and comprising a crank arm 18 and counterweight 19. The thermostatic element 16 is advantageously of the straight bending type, preferably comprising a plurality of flat, flexible, metallic elements, having different coefficients of expansion, secured to each other and suitably mounted in the lower portion of the housing 14 for adjustment of their tension, as by means of a screw 20, and arranged to bear at their free ends against the roller 21 on the crank arm 18, so that under normal temperature conditions the tension exerted by the thermostat against the crank arm will hold the check damper 10 in closed position.

In my improved construction, the end of the crank arm 18 is suitably formed, as for instance, with an eye, 22, to receive the hooked upper end of the connection rod 23, connected at its lower end to the draft damper 13. As is obvious, this construction permits the draft damper 13 to be closed as the check damper 10 is opened, thereby providing a more effective control for the stove.

In order to latch the check damper 10 open and the draft damper 13 closed, and render the thermostatic element inoperative, I have provided a "night" latch member 24 pivotally mounted on suitable journals or trunnions 25 in the housing 14, and having a laterally offset handle portion 26 and a crank portion 27. The crank portion 27 of the "night" latch preferably overlies the crank portion 18 of the operating member 17 so that when the handle portion 26 is moved downwardly (as shown in Fig. 3) the operating member and thermostat elements will be forced rearwardly and downwardly, permitting the check damper 10 to open and closing the draft damper 13. In this position the latch 24 locks the crank arm 18 and check damper 10 in open position with the thermostat in inoperative position so that it cannot operate to control the dampers 10 and 13. When the handle member 25 of the latch is moved to its normal position (as shown in dotted lines in Fig. 3) the tension of the thermostat acting upon the crank member 18 closes the check damper 10 and opens the draft damper 13.

In this position the thermostat is operative to control the dampers 10 and 13.

according to fluctuations in temperature conditions.

The "night" latch may be operated manually or may be connected with suitable 5 time controlled mechanism (not shown) to release it, if desired.

Advantages of my improved damper regulator reside in its adaptability to a large 10 variety of heating apparatus as well as a wide range of automatic control devices such as clocks and the like. Furthermore, it is simple in construction, reliable in operation and not easily broken or deranged. It is an efficient attachment for the purpose 15 of economizing in the consumption of fuel, and for preventing overheating of the apparatus and attendant liability of causing fire; and for maintaining a substantially uniform temperature in the building when 20 desired.

Obviously my invention is not restricted to the details or the illustrative arrangement shown.

I claim:

25 1. A regulator for stoves, furnaces and the like, having check and draft dampers, comprising an operating arm associated with one of said dampers, a flexible thermostat element positioned to engage said arm, means connecting said dampers for simultaneous operation, and latch means positioned for engagement with said arm for locking said thermostat element in a position where it will be ineffective to control 30 said dampers.

2. A regulator for stoves, furnaces and the like, having check and draft dampers connected together for simultaneous operation to reversed positions, comprising an 40 operating arm associated with one of said dampers, a thermostat element positioned to directly engage said arm and adapted in its normal position to hold the check damper closed and the draft damper open, and 45 latch means operative at the will of the operator adapted to engage said arm for locking said thermostat out of its normal position with the check damper open and the draft damper closed.

50 3. A regulator for stoves, furnaces and the like, having check and draft dampers connected together for simultaneous operation to reversed positions, comprising an operating arm associated with said check damper, a thermostat element positioned to directly engage said arm and adapted in its normal position to hold the check damper closed and the draft damper open, and pivoted latch means operative at the will of 55 the operator and having a locking portion engaging said arm for locking said thermostat out of its normal position with the check damper open and the draft damper closed.

60 4. A regulator for stoves, furnaces and

the like, having a check damper pivoted so that it will be opened by gravity and a draft damper pivoted so that it will close by gravity, with means connecting said dampers together for simultaneous operation to reversed positions, comprising a counter-weighted crank arm secured to one of said dampers and movable therewith, a bending bi-metallic thermostat positioned to engage said arm and adapted in its normal position to hold the check damper closed and the draft damper open, and latch means for locking said thermostat out of its normal position, thereby permitting the check damper to open and the draft damper to close. 70 75 80

5. A regulator for stoves, furnaces and the like, having check and draft dampers, connected together for simultaneous operation to reversed positions, comprising an operating arm associated with said check damper, a thermostat element positioned to directly engage said arm and adapted in its normal position to hold the check damper closed and the draft damper open, a housing surrounding said operating arm and thermostat, and 90 a latch member pivotally mounted on said housing and having a portion engaging said arm whereby said latch member may be operated to move said thermostat out of its normal position thereby to lock said check damper open and said draft damper closed. 95 100

6. A regulator for stoves, furnaces and the like, having a check damper pivoted so that it will be opened by gravity and a draft damper pivoted so that it will close by gravity, with means connecting said dampers together for simultaneous operation to reversed positions, comprising a counter-weighted crank arm secured to said check damper and movable therewith, a bending bi-metallic thermostat positioned to engage said arm and adapted in its normal position to hold the check damper closed and the draft damper open, and pivotally mounted latch means having a portion engaging said arm, locking said thermostat out of its normal position, thereby permitting the check damper to open and the draft damper to close. 105 110 115

7. A regulator for stoves, furnaces and the like, having check and draft dampers, an operating crank arm on said check damper and movable therewith, and a bending thermostat secured at one end below said check damper and having its free end engaging said crank arm, and a connecting rod pivotally connected with said crank arm and draft damper for operating said check and draft dampers simultaneously in reverse directions. 120 125

8. A regulator for stoves, furnaces and the like, having check and draft dampers, an operating crank arm on said check damper and movable therewith, and a bending thermostat secured at one end below said check damper and having its free end engaging 130 135

said crank arm, an eye formed on said crank arm, and a connecting rod pivotally connected with said eye and said draft damper for operating said check and draft dampers in reverse directions.

9. A regulator for stoves, furnaces and the like, having a check damper 10 and draft damper 13, and operating crank arm 18 connected with said check damper, a thermostatic stat 16 engaging said arm 18, a connecting

rod 23 connecting said arm 18 and draft damper 13 whereby said dampers may be operated simultaneously to reversed positions, and a night latch 24 adapted to engage said arm 18 to hold said check damper open ¹⁵ and said draft damper closed and said thermostat out of its normal position.

In testimony whereof, I have signed my name to this specification.

LESLIE DANA.
